CLAIM

The ornamental design for a holding bin user interface, as shown and described.

DESCRIPTION

FIG. 1 is a front view of a holding bin with a top panel user interface and a side panel user interface.

FIG. 2 is a perspective view thereof; and,

FIGS. 3-7 present an enlarged detailed view of a succession of presentations of a top panel user interface of FIGS. 1 and 2.

The broken lines showing of various portions and other elements in the Figures are for the purpose of illustrating unclaimed portions and form no part of the claimed design. The Figures include cross-hatching and stippling to denote color. Regions of the same cross-hatching or stippling denote the same color while regions of different cross-hatching or stippling denote different colors.
